UNITED STATES PATENT OFFICE.

JOSEPH B. LONG, OF CHICAGO, ILLINOIS.

DESIGN FOR A CADDY.

SPECIFICATION forming part of Design No. 33,803, dated December 25, 1900.

Application filed August 20, 1900. Serial No. 27,506. Term of patent 3½ years.

To all whom it may concern:

Be it known that I, JOSEPH B. LONG, a citizen of the United States, residing at Chicago, in the county of Cook and State of Illinois, 5 have invented and produced a new and original Design for Caddies, of which the following is a specification, reference being had to the accompanying drawings, which are made a part of said specification, and in which—

10 Figure 1 is a perspective view of a caddy embodying the new design. Fig. 2 is an end elevation thereof.

A caddy of the new design has a body of substantially rectangular shape in horizontal 15 section. Its back and end walls are flat and vertical, while the outer face of its front wall comprises a panel C, surmounted by a narrow raised strip or rib D, both extending from end to end of the body. The outer face of 20 the panel C is curved in vertical planes and the rib D has along its horizontal margins inturned flanges d. The top of the caddy comprises a narrow flat strip E, disposed horizontally, and a flat lid F, extending from end 25 to end of the body, which lid inclines downward and forward, the ends G being corre-

spondingly inclined. The body is supported by legs H at its four corners.

The leading essential features of the new design are the body having at the front the 30 panel C, the outer surface of which is curved in vertical planes, and the flat inclined lid F, extending from end to end of the body, the ends G being correspondingly inclined.

Minor features of the design are the narrow raised rib D, extending along the upper margin of the curved panel C, the inturned flanges d, extending along the horizontal margins of the rib D, and the legs at the four 35 corners of a body having the general shape 40 and configuration above described.

What I claim as new, and desire to secure by Letters Patent, is—

The design for a caddy substantially as herein shown and described. 45

Signed at Chicago, Illinois, this 30th day of July, 1900.

J. B. LONG.
